UNITED STATES PATENT OFFICE.

DANIEL A. SMITH, OF DRUMMOND, MARYLAND, AND JOHN P. MANN, OF WASHINGTON, DISTRICT OF COLUMBIA, ASSIGNEES TO DISTRICT OF COLUMBIA PAPER MANUFACTURING COMPANY, OF WASHINGTON, DISTRICT OF COLUMBIA, A CORPORATION OF VIRGINIA.

PAPER-MAKING MACHINE.

992,695.

Specification of Letters Patent. Patented May 16, 1911.

Application filed March 2, 1911. Serial No. 611,793.

To all whom it may concern:

Be it known that we, DANIEL A. SMITH, of Drummond, in the county of Montgomery and State of Maryland, and JOHN P. MANN, of Washington, District of Columbia, citizens of the United States, have invented certain new and useful Improvements in Paper-Making Machines, of which the following is a full and complete specification.

Our invention is an improvement in paper-making machines, and is more especially an attachment which is adapted to operate on the paper stock or layer of pulp during the "making" of the paper, so that the finished product will have stripes of different characteristics.

Our invention relates more especially to an attachment for Fourdrinier machines, and the primary object of the present invention is to provide an attachment which will operate on the layer of pulp somewhere between the slices and couch-rolls to displace and aggregate fibers of the pulp in such manner that the finished paper will have distinct stripes of mottled appearance in the nature of a water mark, such stripes in the present instance alternating with plain stripes to produce an ornamental paper.

A further object of the present invention is to provide an apparatus for coloring or tinting the "mottled stripe" during the formation of the same.

In the present instance we accomplish these objects by the employment of a drag having spaced apart portions which impose pressure upon the surface of the layer of pulp to displace and aggregate fibers of the pulp in a line or stripe, and apply the color or tint through the medium of the spaced apart engaging portions of the drag; all as hereinafter fully set forth and claimed.

In the accompanying drawings, which form a part of this specification:—Figure 1 is a plan view, showing the application of the striping device and including the apparatus for tinting the stripes. Fig. 2 is a vertical sectional view through one of the tanks employed in supplying the color to the striping devices, the section being on the line 2—2 of Fig. 1. Fig. 3 is a sectional view on the line 3—3 of Fig. 1.

Like numerals of reference indicate like parts in all the figures of the drawings.

Our attachment is especially adapted for application to Fourdrinier paper-making machines in which the pulp or paper stock is fed from the slices on to a wire in the form of a layer or sheet and supported by said wire during the operation of extracting the water, or most of it, before the layer of pulp reaches the rollers. In this form of machine the attachment is applied above the wire and layer of pulp somewhere between the slices and dandy-roll so that it may act upon the fibers of the pulp before they become set.

Referring now to the drawings, 5 designates a supporting-wire of a Fourdrinier paper-making machine, and 6 designates a layer of pulp carried by the wire in the operation of making paper. Suitably supported above the wire and layer of pulp thereon is a strip of felt or other material, as 7, one edge of which is cut away at intervals to provide a number of spaced apart portions or members 7^a, adapted in the present instance to drag upon the layer of pulp and displace the fibers in such manner that the finished paper will show distinct stripes.

In the present instance the strip of material 7 is supported by means of a cross-bar 8, to which it is attached at one end so that the spaced apart portions 7^a at the other end may drag upon the layer of pulp. The ends 85 of the cross-bar 8 may, and preferably do, project beyond the edges of the wire so as to support the bar and strip of material from the side rails of the machine. It will be understood, of course, that instead of providing a single sheet of felt or material having its outer edge cut away to form the engaging portions 7^a, the latter may be formed by separate strips, but the advantage of the particular device shown will be apparent, inasmuch as the body portion of the strip will serve to hold the engaging portions at the desired spaces apart.

In operation, the portions 7^a by dragging upon the surface of the layer of pulp displace or rolls some of the fibers into irregularly formed groups which are not affected by the further "making" of the paper, and when the web passes from the

rolls it will be seen that these "groups" of fibers assume a distinct appearance, being in the form of peculiarly shaped lines, principally wavy, and of a different shade than the body of the paper. As the engaging portions 7^a are spaced apart the finished paper will have stripes in which the wavy lines or markings appear, these stripes so formed alternating with plain stripes resulting from that part of the layer of pulp between the engaging portions. When the strip of material 7 is held stationary the stripes will be straight, and in order to produce wavy stripes it will only be necessary to impart to the material 7 a lateral movement during the operation of the attachment. Furthermore, as will be obvious, paper having a checkered design may be produced by lifting the engaging portions 20 at intervals.

As heretofore stated, the stripes which appear on the finished paper by reason of the wavy lines or markings formed during the making of the paper are very distinct and produce a paper of ornamental character; but in some instances it is desired that these stripes be of a different color or tint from the other or plain stripes, and in order to accomplish this we provide an apparatus for feeding color to the spaced apart engaging portions 7^a. This apparatus comprises a mixing vat 9, connected to a supply tank 10, from which extends a distributing pipe 11 having cocks 12 which discharge directly upon the engaging portions 7^a of the drag 7, the distributing-pipe being provided with a valve 13 for controlling the supply to the cocks. In the present instance the supply tank 10 is provided with two compartments, 10^a and 10^b, separated by a partition 14, and the upper edge of this partition terminates a slight distance below the upper end of the tank so that the liquid or color mixture may overflow from one compartment to the other, for the purpose hereinafter explained. The tank 10 is supplied from the vat 9 by means of a pump 15 and pipes 16, 16, one of the latter extending from the lower portion of the vat while the other enters the bottom of the compartment 10^a of the supply tank. There is also a drain pipe, 17, extending from the bottom of the compartment 10^b of the supply-tank into the vat. In the operation of this color supplying apparatus the pump 15 is run so as to supply the liquid or mixture a little faster than it is taken off by the distributing pipe 11 which is connected to the compartment 10^a, so that the excess will overflow the partition 14 into the compartment 10^b and return to the mixing vat by way of the drain pipe 17. As will be seen, therefore, there is a constant agitation of the color mixture in both the supply tank and vat, which will serve to keep the color thoroughly mixed at all times and therefore

supply an even color or tint to the engaging portions of the drag. By providing separate cocks for each engaging portion of the drag the amount of color mixture supplied to each may be independently regulated, and this is necessary owing to the decreasing pressure from cock to cock. 79

In case stripes of different color should be required the apparatus described may be duplicated, as will be obvious. 75

Having thus described our invention, what we claim as new, and desire to secure by Letters-Patent, is:—

1. An attachment for paper-making machines, comprising means spaced apart and dragging over the surface of the layer of pulp to displace and aggregate some of the fibers, substantially as shown and described. 80

2. An attachment for paper making machines, comprising a strip of material having spaced apart portions which drag over the surface of the layer of pulp to displace and aggregate some of the fibers, substantially as shown and for the purpose set forth. 85

3. An attachment for paper-making machines, comprising a supporting-bar, and means carried thereby and presenting spaced apart portions or members which drag over the surface of the layer of pulp to displace and aggregate some of the fibers, substantially as shown and for the purpose set forth. 90

4. An attachment for paper-making machines, comprising a supporting bar, and a strip of material attached thereto and cut away at its outer edge to provide spaced apart portions or members which drag over the surface of the layer of pulp to displace and aggregate some of the fibers, substantially as shown and for the purpose set forth. 95

5. An attachment for paper making machines, comprising spaced apart portions or fabric which drag over the surface of the layer of pulp, and means for discharging color on the engaging portions or fabric, substantially as shown and for the purpose set forth. 100

6. An attachment for paper-making machines, comprising spaced apart strips of fabric which drag over the surface of the layer of pulp to displace and aggregate some of the fibers, a color supply tank having a discharge pipe with cocks discharging on the strips of fabric, a mixing-vat, means for conducting the overflow from the supply-tank into the mixing-vat, and a pump for supplying the supply-tank from the mixing-vat, substantially as shown and for the purpose set forth. 115

7. An attachment for paper-making machines, comprising spaced apart strips of fabric which drag over the surface of the layer of pulp to displace and aggregate some of the fibers, a color supply tank having two compartments with a partition over which the contents of one may flow into the 120

other, a discharge-pipe from one of the compartments of the supply-tank having cocks discharging on the strips of fabric, a mixing-vat, a pump taking from the vat and discharging in one of the compartments of the supply-tank, and a drain from the other compartment of the supply-tank to the vat, substantially as shown and described.

In testimony whereof we have signed our names to this specification in the presence of two subscribing witnesses.
